CLOSURE FOR UNREFILLABLE CONTAINERS

Jose Soto del Llano, Havana, Cuba, assignor of
one-fourth to Ricardo More Ferrer, Havana,
Cuba

Application May 5, 1950, Serial No. 160,140

1 Claim. (Cl. 215—23)

1

This invention relates to closures for unrefillable containers, particularly to closures of that kind which are provided with a weight connected to the valve by flexible means, and it has for its object to provide an improvement in the closure device which is the subject-matter of my United States Patent No. 2,420,870, granted May 20, 1947.

The improvement forming the object of this invention consists in that the valve is carried by a single member in the shape of a sleeve provided with a top horizontal flange adapted to rest on the container top edge, which sleeve forms a central seat on which the valve is adapted to rest, the lower face of the latter remaining inserted within the container neck below the level of the joint between the closure horizontal flange and the top edge of the container so that the valve cannot be raised from its seat by means of a perforating instrument inserted through the packing and the outer casing of the closure at the joint between the closure horizontal flange and the top edge of the container, nor can the valve be destroyed across the top opening of the closure casing with a view to allowing the passage into the container of a liquor of inferior quality for refilling purposes, whereby this new closure is rendered more safe against violations for refilling purposes as well as more economical to manufacture by reason of the fact that the valve carrying member is limited to a single member and the height of the outer casing is reduced.

The invention is described with reference to the figures of the accompanying drawing, of which:

Fig. 1 is a diametral vertical section view of the closure and a bottle neck provided with the closure in the normal or upright position of the bottle.

Fig. 2 is a sectional view similar to that of Fig. 1, showing the bottle in an inclined or inverted position.

Fig. 3 is a detailed view showing the closure outer casing partly in outer elevation and partly in diametral vertical section.

Fig. 4 is a detailed bottom plan view of the closure outer casing.

Fig. 5 is a detailed view showing the sole member forming the valve carrying element, partly in elevation and partly in diametral vertical section.

Fig. 6 is a detailed bottom plan view of the sole member forming the valve-carrier.

Fig. 7 is a perspective view of the unborable metal disc that is loosely superposed to the spaced raised projections formed at the top edge of the valve-carrier.

2

Fig. 8 is an outer elevational detailed view of the valve and its guide cross-piece.

Fig. 9 is a detailed bottom plan view of the valve.

5 Fig. 10 is a perspective view of the valve and its depending weight.

The closure of this invention comprises a valve-carrier formed by a single member in the shape of a plastic or metal sleeve 1 adapted to be inserted in the neck of a bottle 2 and provided with a horizontal flange 3 by which it rests on the upper edge of the bottle 2. The sleeve 1 has a lower horizontal disc 4 provided with a central opening 5 having a top raised rim 6 forming the seat for the valve, and from said disc downwardly lead a plurality of spaced apart vertical plane wings 7 disposed radially and having at their lower inner corner a bevelled cut 7' to provide interspaces 8 for the passage of liquid 9 from the bottle towards the central opening 5 of the disc 4. At the top edge of the sleeve 1 are raised a plurality of spaced apart vertical projections 10, as for instance four in number, which provide openings 11 for the passage of the liquid, and the top 15 face of which is adapted to serve as a rest for a loose unborable hard-steel disc 12 adapted to protect the valve.

The hollow valve 13 is cylindrical and closed both on top and at the bottom, though it may be open on top if desired, and from the lower base thereof leads a cross-piece formed by four wings 14 and 15 of dissimilar length those at the different plane, all four wings 14 and 15 being lodged through the central opening 5 of the disc 4 to serve as a guide for the valve 13 in its upward and downward movement. The two longer wings 15 are joined together beneath the two shorter wings 14 to form an eye 15' splitted at one side for its flexible connection with the ring 16 formed at the top end of the weight 17 of double frustro-conical shape having its largest cross-section at the centre thereof, and which has a lower central recess 18 within which is inserted a cylindrical socket 19 carrying a metal ball 20 and which is secured in position by means of glue.

The cylindrical casing 21 is inferiorly open and tapering upwardly to end at its top in an upper central opening 22 adapted to be closed by a cork stopper 23, said casing having a lower enlarged portion 21' the lower edge of which rests on the horizontal flange of the sleeve 1. Said casing 21 is provided interiorly with four spaced apart vertical depending wings 24 dividing the inner hollow space of the casing into four conduits for the passage of liquid from the bottle, and said wings

24 have a right angle cut 25 at their lower projecting corner to form a lock against the edge of the hard-steel disc 12 resting on the top faces of the vertical projections 10 of sleeve 1.

The casing 21 is inviolably secured to the bottle 2 by means of a metallic packing 26, preferably made of aluminum, which is bent at its top edge upon the top edge of the lower enlarged portion 21' of the casing, and the same is bent at its lower edge below the annular shoulder 21 formed on the neck of bottle 2.

In order to prevent that an instrument as a wire may be inserted downwards the peripheral conduits of the casing, said opening is provided with a lower depending rim 28.

The operation of this closure is as follows: As the bottle 2 is inverted to discharge the inner liquid 9 (Fig. 2), the valve 13 will fall and the wings 14 and 15 thereof will slide within the guide formed by the seat 6 connected to the sleeve 1, until the upper cone of the weight 17 abuts against the bevelled corners 1' of the wings 7 of sleeve 1, whereupon the liquid 9 will pass through the interspaces 8 formed between said wings toward the central opening 5 of the disc 4 forming the seat 6 for the valve, and from the central opening 5 the liquid 9 passes through the interspaces between the wings 14 and 15 of the valve, to find its way through the hollow of sleeve 1 about the valve 13 towards the openings 11 between the raised projections 10. The liquid 9 then penetrates in the inner hollow space 29 of the casing 21 and from there it passes through the inner conduits of the casing 21 between the depending wings 24 towards the inner space 30 above the hard-steel disc 12, and then through the top central opening 22 of the casing 21 wherefrom it is discharged, once the cork stopper 23 is removed.

It is obvious that by reason of the fact that the lower face of the valve 13 remains, either in its normal position or in its raised position on its seat, at a level below the joint between the horizontal flange 3 of the sleeve 1 and the top edge of the bottle 2, it will not be possible to introduce through the packing 26 and said joint a piercing instrument for the purpose of retaining the valve raised on its seat and thus permit the refilling of the bottle through the top opening 22 and the sinuous conduits of the closure. Preferably, the sleeve should be made sufficiently long so that as the bottle is inverted (Fig. 2), the top face of the valve will not project beyond the level of the joint between the horizontal flange of the sleeve 1 and the top edge of the bottle 2, thereby preventing the valve 13 from being engaged with a piercing instrument inserted through the packing 26 and said joint for the purpose of retaining the valve raised on its seat and thus permit the refilling of the bottle 2. It would not also be possible to destroy the valve 13 by forcing a piercing instrument through the top opening 22, as the strike of such instrument would be absorbed by

the unborable hard metallic disc 12 that thus effectively protects the valve 13.

Inasmuch as the valve carrying member of this closure is limited to a single element which permits a reduction in the height of the closure, this closure will be rendered more economical to manufacture in relation to the closure which was the subject-matter of my United States Patent No. 2,420,870, granted May 20, 1947.

10 It is obvious that changes may be made within certain limits in the inner shape as well as in the number of inner passageways or conduits formed by the sleeve wings and projections and by the casing depending wings, without thereby 15 altering the essential character of the invention, which is such as claimed hereinafter.

What I claim is:

A closure for unrefillable containers, comprising a valve-carrier formed by a sleeve lodged within the bottle neck and provided with a top horizontal flange adapted to rest on the top edge of the bottle, the sleeve having a disc at its lower end with a central opening and a rim raised on the edge of said opening to serve as a seat and 20 a guide for the valve, and the sleeve having spaced apart raised projections projecting upwardly from its top edge to form openings for the passage of liquid, radially spaced apart vertical wings downwardly projecting from the disc 25 secured to the sleeve and having their lower inner corner bevelled, a hard metal disc resting on the top projections of the sleeve, a hollow cylindrical valve normally resting on the raised rim bordering the opening of the disc joined to the sleeve 30 and having four lower vertical wings in the shape of a cross-piece of which two wings are longer than the other two and all are lodged through the opening of the disc joined to the sleeve and adapted to run within said opening and within 35 the space bordered by the wings downwardly projecting from the disc, a weight flexibly connected to the two longer opposed wings of the valve, an upward tapering cylindrical casing having a central opening and having a lower edge resting 40 on the sleeve flange, said casing having interiorly 45 thereof spaced vertical depending wings forming passageways for the liquid about the raised projections of the sleeve, and means for inviolably securing the casing on the bottle neck.

JOSE SOTO DEL LLANO.
